DESIGN FOR A TEACUP

Marion L. Hubbard, Carmel, N. Y.

Application July 24, 1945, Serial No. 120,926

Term of patent 14 years

(Cl. D44—9)

To all whom it may concern:

Be it known that I, Marion L. Hubbard, a citizen of the United States, residing at Carmel, in the county of Putnam and State of New York, have invented a new, original, and ornamental Design for a Teacup, of which the following is a specification, reference being had to the accompanying drawing forming part thereof, in which Fig. 1 is a plan view of a teacup showing my new design, and

Fig. 2 is an elevational view thereof.

I claim:

The ornamental design for a teacup, as shown.

MARION L. HUBBARD.
